UNITED STATES PATENT OFFICE.

GEORGE E. OUTLAW, OF VAUGHN, NEW MEXICO.

DRAFT-RIGGING.

1,361,543.

Specification of Letters Patent. Patented Dec. 7, 1920.

Application filed July 26, 1919. Serial No. 313,473.

To all whom it may concern:

Be it known that I, GEORGE E. OUTLAW, a citizen of the United States, residing at Vaughn, Guadalupe county, State of New Mexico, have invented certain new and useful Improvements in Draft-Rigging, of which the following is a specification, reference being had therein to the accompanying drawings.

10 This invention relates to draft-rigging for railway-cars of the type that includes means that imposes both friction and spring resistance to draft and buffing strains.

15 Among the objects of the invention are to arrange the several parts in such manner that the comparatively few parts that may require renewal may be removed easily without interference with the rigging as a whole; to form and assemble the parts so 20 that those most apt to require attention may be inspected without opening or loosening other parts; and to provide draft-rigging that may be installed and removed and the parts of which may be renewed 25 from the outer ends of the draft-arms and from the sides of them.

When considered in connection with the description herein, the details of construction and arrangement of parts contemplated 30 by the invention will be apparent from the accompanying drawings, forming part hereof, wherein an embodiment of the invention is disclosed, for the purpose of illustration.

35 While the disclosures herein now are considered to exemplify a preferable embodiment of the invention, it is to be understood that it is not the intention to be limited necessarily thereto in interpretation of the 40 claims, as alterations and adaptations within the limits of the claims can be made without departing from the nature and spirit of the invention.

Like reference-characters refer to corresponding parts in the views of the drawings, of which—

Figure 1 is a plan view, certain parts being broken away;

Fig. 2 is a horizontal sectional view;

50 Fig. 3 is a vertical sectional view;

Fig. 4 is a side view;

Fig. 5 is a transverse sectional view on the line 5—5, Fig. 1;

Fig. 6 is a view of one of the main friction-blocks;

Fig. 7 is a plan view of the bull-block;

Fig. 8 is a side view of the bull-block;

Fig. 9 is a transverse sectional view on the line 9—9, Fig. 2; and

Fig. 10 is a fragmentary horizontal sectional view showing the position of certain parts under buffing strain.

Referring more particularly to the drawings, 11 designates two separated substantially parallel draft sills or members, preferably channel irons, extending longitudinally of the under portion of the car-body and centered on its axis. The draft sills have aligned openings 12 in their webs near the end of the car.

For the purpose of communicating strains from the draft-rigging to the draft-sills, a reinforcing-plate 13 is secured to the web of each sill on each side of its opening and extends from top to bottom thereof; the material of each plate extends outwardly through each opening as a guide-flange 14; complementary pairs of guide members 15 extend inwardly of the sills, one pair being located at the upper and lower ends of each opening and projecting for a portion of the distance across the space between the sills; and reinforcing plates 16 extend from the upper and lower edges of the plates 13 for a portion of the distance across the space between the sills, the oppositely disposed marginal portions of plates 16 constituting guides, and the guide members 15 being secured to plates 16 and to flanges 14. These parts may be integrally associated or 90 welded or otherwise secured together. A covering-plate 17 extending from one draft sill to the other may be secured to the outside of each pair of plates 16.

Draft and buffing strains sustained by a 95 coupler-head 18 at the end of the car are imposed, by means of a coupler-shank 19 and a key 20, on arms 21 of a draw member or bull-block 22, the arms extending on each side of the shank. The key is of such 100 length that it is prevented from displacement by contact with the sills. The block

has abutments 23 on its upper and lower sides, each of which extends and fits snugly between the inner ends of the guide members 15, and the sides of the block fit snugly 5 against these guide members, the arrangement being such as to prevent twisting movement of the block.

The bull-block has on each side near its inner end a recess 24, the two recesses being 10 oppositely disposed. Each end wall of each recess extends for a short distance inwardly and at substantially right angles to the side of the block, whereby oppositely-disposed abutments 25 are afforded. The end walls 15 of a recess converge toward each other from the abutments toward the bottom, whereby friction-surfaces 26 oppositely inclined to the line of draft are provided.

A friction-block 27, wedge shaped on its 20 inner end to conform to the inclination of the friction-surfaces 26, seats in each recess 24, and is disposed between upper and lower pairs of guide members 15, and it has on its upper and lower sides abutments 28, 25 each of which extends between a pair of those guide members, which guide the friction-block in its movement transversely of the line of draft and take draft and buffing strains.

30 The outer end of each friction-block also is wedge shaped or formed with surfaces 29, which are inclined with respect to the transverse axis of the rigging, and against those surfaces are positioned counter-balance 35 wedge-blocks 30, which contact with the guide-flanges 14 and keep the friction-blocks at right angles to the bull-block. In the embodiment shown, the wedge-blocks are right-triangular in cross-section, the hypotenuse sides rest against the friction-block, and the leg sides contact with the guide flanges.

The sides of the friction-blocks between the wedge-shaped ends are substantially 45 parallel and straight.

In order to keep the wedge members in place and to contribute to the resistance thereof to movement as a result of strains imposed on the bull-block, a bearing-plate 50 31 is pressed against the outer sides of each set of wedge-blocks by a presser-plate or member 32 connected by bolts or the like 33 to the ends of a pair of auxiliary leaf-springs 34, the springs being located outside of the 55 draft members. The opposite ends of these springs are held in a saddle 35, as are also a pair of main springs 36 separated therefrom by a spacing member 37, by a bolt 38 and a cap 39 drawn by the nut of the bolt 60 against the main springs. The saddle has pairs of lugs 40, and pins 41 pass through those lugs and through members 42 on a sill, on the outside of which the saddle thus is mounted pivotally. The main springs, 65 which are shorter than the auxiliary ones,

have a tie member 43 bearing against the end portions opposite to the saddle, and a bolt 44 extending between the springs through the tie member has a nut 45 on one end portion outside of that member. The other end 70 of the bolt has an enlarged portion 46, and a pin 47 extends therethrough and through lugs 48 on the sill, on which the bolt thus is pivotally mounted.

When the bull-block sustains draft or 75 buffing strains sufficient to overcome the frictional and spring resistance in the friction members, the friction-blocks are given outward movement by operation of the friction-surfaces 26 thereon. Such movement is resisted by the friction of those surfaces, of the friction-blocks against the guide-flanges, and it also is resisted by the springs. If the strain is sufficiently great and sustained, the bull-block will move until its abutments 25 80 engage straight sides of the friction-blocks (as shown by Fig. 10), when movement of the bull-block will be stopped, and displacement thereof prevented.

The resistance of the friction members to 90 movement of the bull-block may be altered by adjustment of the tension of the springs, which may be effected by turning nuts 45 away from the free ends of their bolts to draw the main springs toward the auxiliary 95 ones and thereby cause greater pressure or by turning them in the reverse direction and causing less pressure. Of course, alteration of spring tension not only changes the direct resistance of the springs to movement of the 100 friction members and thereby to the bull-block, but it also affects frictional resistance, which is greater or less as the spring tension is greater or less.

As strains upon the bull-block are lessened, the friction members will be moved by the springs toward or to normal positions.

It will be seen that the springs are located at the sides of and outside of the draft-sills, 110 where they are easily accessible for adjustment without removing other parts, and where they may be removed and replaced without interference with or removal of friction members or other parts. The friction members themselves on either side may be removed and replaced, after becoming worn or for any other reason, without disturbing those on the other side. All that is necessary for such an operation is to remove 115 nut 45 and tie member 43 and then to swing the springs on their saddle 35 out of the way, whereupon the bearing-plate 31 and the friction parts thereunder are easily accessible through the opening 12.

Moreover, in order to remove the bull-block itself, if that is necessary, all that is required is to swing the springs out of the way on each side, as already described for one side, and then withdraw the bearing- 130

plates and friction members, when the bull-block is free to be pulled out from parts between which it has been held; and replacement of the parts can be effected just as 5 readily by reversal of this operation.

No bolts, other than those controlling the tension of the springs, and no straps or like parts are involved in this rigging; and, therefore, liability of parts becoming 10 displaced and lost and the work of adjustment of parts and their removal and replacement are reduced to a minimum.

What I claim as new, and desire to secure by Letters Patent, is—

15 1. In draft-rigging, the combination, with spaced draft members, of a draw member therebetween having a recess with walls oppositely inclined to the line of draft, a friction-block wedge-shaped at both ends seated 20 in said recess, wedge-blocks at the outer end of said friction-block, guideways for said friction-block and wedge-blocks, and means pressing said wedge-blocks and friction-block toward said draw member.

25 2. In draft-rigging, the combination, with spaced draft members, of a draw member therebetween having a recess with walls oppositely inclined to the line of draft, a friction-block wedge-shaped at both ends seated 30 in said recess, wedge-blocks at the outer end of said friction-block, a bearing member against said wedge-blocks, guideways for said friction-block, wedge-blocks, and bearing member, and means exerting pressure 35 inwardly against said bearing member.

35 3. In draft-rigging, the combination, with spaced draft members, of a draw member therebetween having a recess with walls oppositely inclined to the line of draft, a friction-block wedge-shaped at both ends seated 40 in said recess, wedge-blocks at the outer end of said friction-block, a bearing member against said wedge-blocks, guideways for said friction-block, wedge-blocks, and bearing member, a leaf-spring exerting pressure at one end inwardly against said bearing member, a saddle pivotally mounted outside of one of said draft members and holding the other end portion of said spring, 45 another spring extending from said saddle, and means in engagement with said latter spring whereby to adjust spring tension.

45 4. In draft-rigging, the combination, with spaced draft members, of a draw member 50 therebetween having a recess with walls oppositely inclined to the line of draft, a friction-block wedge-shaped at both ends seated in said recess, wedge-blocks at the outer end of said friction-block, a bearing member 55 against said wedge-blocks, guideways for said friction-block, wedge-blocks, and bearing member, a leaf-spring exerting pressure at one end inwardly against said bearing member, a saddle pivotally mounted outside of one of said draft members and hold-

ing the other end portion of said spring, another spring extending from said saddle, a bolt pivotally connected to one of said draft members, and a nut on said bolt arranged to draw said latter spring toward 70 the former.

5. In draft-rigging, the combination, with spaced draft members, of a draw member therebetween having a recess with walls oppositely inclined to the line of draft, a friction-block having a wedge-shaped end seated in said recess, guideways for said block, and means operating to press said friction-block toward said draw member, said means including a pair of leaf-springs at the outer 80 side of one of said draft members and operating at one end against said friction-block, a saddle pivotally mounted on a fixed part in engagement with the other end of the springs, another pair of springs extending 85 from said saddle, a spacing member between each pair of springs, a cap and bolt holding said springs in said saddle, a tie member at the opposite ends of said latter springs, a bolt pivotally mounted on a fixed part, 90 and a nut on said bolt coöperating with said cap whereby said springs are maintained under tension.

6. In draft-rigging, the combination, with spaced draft members one of which has an 95 opening therein, of flanges at said opening, guideways extending inwardly from said opening, a draw member between said draft members having a recess with walls oppositely inclined to the line of draft, a friction-block wedge-shaped at both ends seated 100 in said recess and movable in said guideways, wedge-blocks bearing against the outer end of said friction-block and against said flanges, and means pressing said wedge-blocks and friction-block toward said draw member.

7. In draft-rigging, the combination, with spaced draft members one of which has an 110 opening therein, of flanges at said opening, guideways extending inwardly from said opening, a draw member between said draft members having a recess with walls oppositely inclined to the line of draft, a friction-block wedge-shaped at both ends seated 115 in said recess and movable in said guideways, wedge-blocks bearing against the outer end of said friction block and against said flanges, a bearing member between said flanges, and means pressing said bearing member inwardly against said wedge-blocks.

8. In draft-rigging, the combination, with spaced draft members, of complementary 120 pairs of guide members extending inwardly from said draft members, reinforcing-plates 125 to which said guide members are secured extending from said draft members, a draw member between said draft and guide members having a recess with walls oppositely inclined to the line of draft, abutments on 130

said draft member extending between the ends of said guide members, a friction-block movable in said guide members and having a wedge-shaped end seated in said recess, 5 and means pressing said friction-block toward said draw member.

9. In draft-rigging, the combination, with spaced draft members one of which has an opening therein, of flanges at said opening, 10 guideways extending inwardly from said opening, a draw member between said draft members and guideways having a recess with walls oppositely inclined to the line of draft, abutments on said draft member 15 extending between ends of said guideways, a friction-block movable in said guideways and having a wedge-shaped end seated in said recess, and means pressing said friction-block toward said draw member.

20 10. In draft-rigging, the combination, with spaced draft members having oppositely-disposed openings therein, of a draw member therebetween having oppositely-disposed recesses with walls oppositely inclined to the line of draft, friction-blocks 25

wedge-shaped at both ends seated in said recesses, wedge-blocks at the outer end of each friction-block, guideways for said friction and wedge-blocks, and oppositely-acting means pressing said wedge and friction 30 blocks toward said draw member.

11. In draft-rigging, the combination, with spaced draft members having oppositely-disposed openings therein, of a draw member therebetween having oppositely-disposed recesses with walls oppositely inclined to the line of draft, friction-blocks 35 each of which has a wedge-shaped end seated in one of said recesses, guideways for said friction-blocks, leaf-springs, one on the outside of each draft member, oppositely pressing at their ends the friction-blocks toward said draw member, saddles pivotally mounted on said draft members and holding the other end portions of said springs, other 40 springs extending from said saddles, and means in engagement with said latter springs whereby to adjust spring tension.

In testimony whereof I affix my signature.
GEORGE E. OUTLAW.
